UNITED STATES PATENT OFFICE.

CEPHAS B. ROGERS, OF DANBURY, CONNECTICUT.

DESIGN FOR AN INKSTAND.

No. 37,941.

Specification for Design.

Patented April 10, 1906.

Application filed March 9, 1905. Serial No. 249,282. Term of patent 3½ years.

To all whom it may concern:

Be it known that I, CEPHAS B. ROGERS, a citizen of the United States, residing at Danbury, in the county of Fairfield and State of Connecticut, have invented a new, original, and ornamental Design for Inkstands, of which the following is a specification, reference being had to the accompanying drawings, forming a part thereof.

In the drawings, Figure 1 is a plan view,

and Fig. 2 a side elevation, of an inkstand, showing my new design.

I claim—

The ornamental design for an inkstand, as shown.

CEPHAS B. ROGERS.
